CLAIM

The ornamental design for a free standing hose hanger, as shown and described.

DESCRIPTION

FIG. 1 is a perspective view of a free standing hose hanger showing our new design with the lower portion of the post broken away for convenience of illustration;

FIG. 2 is a side elevational view of a free standing hose hanger on a reduced scale, for which the opposite side view is a mirror image of same;

FIG. 3 is a top view of a free standing hose hanger on a reduced scale;

FIG. 4 is a bottom view of a free standing hose hanger on a reduced scale;

FIG. 5 is a front elevational view of a free standing hose hanger on a reduced scale; and,

FIG. 6 is a rear elevational view of a free standing hose hanger on a reduced scale.

The broken line showing of a hose faucet fitting and a hose connection fitting in FIGS. 1, 2, 3, 4, 5 and 6 is for illustrative purposes only and forms no part of the claimed design.
